(57) **CLAIM**

We claim the ornamental design for a canopy for a fuel dispensing station, as shown and described.

DESCRIPTION

FIG. 1 is a perspective view of the canopy for a fuel dispensing station showing the design;

FIG. 2 is a front view thereof;

FIG. 3 is a rear view thereof;

FIG. 4 is a top view thereof;

FIG. 5 is a bottom view thereof;

FIG. 6 is an end view thereof; and,

FIG. 7 is an end view thereof, opposite the end view shown in FIG. 6.

The broken lines shown are for illustrative purposes only and form no part of the claimed design.
